Application June 16, 1953, Serial No. 362,114

8 Claims. (Cl. 299—107.8)

1

This invention relates to internal combustion engines of the compression ignition type and has particular reference to new and improved fuel injection apparatus therefor.

In the early days of compression ignition engines which operated on the true diesel cycle, the advantages of the conservative maximum firing pressure characteristic of the constant pressure mode of combustion were seriously offset by the hazard of explosions in the blast air compressing and storing means. Furthermore, the air compressor was relatively unreliable. In these early true diesel engines, it was necessary to have available a stored supply of air compressed to a pressure in the order of 1000 p. s. i. and this supply of blast air had to be maintained at such high pressure during operation of the engine by means of an air compressor. The blast air usually constituted as much as 5% to 8% of the total air consumption of the engine; and consequently a considerable percentage of the gross power output of the engine was necessarily diverted for driving the blast air compressor. An undesirably high specific fuel consumption of the engine accordingly resulted.

In these diesel engines, although a lower blast pressure was required at light engine loads than at full load, the stored supply of blast air had to be continuously maintained at the highest pressure which might from time to time be required. The practice of compressing and storing the air at high pressure and then reducing it to a lower pressure for use at light loads was exceedingly inefficient. The part-load economy of the engine was adversely affected because of the even greater proportionate diversion of engine power for driving the blast air compressor under light load conditions of engine operation.

In all these diesel engines, control of the admission of blast air to the injector was effected by a mechanically actuated air valve which could be controlled as to the amount and duration of lift per cycle, the duration being referred to degrees of crankshaft rotation. Since a given setting of the air valve control would admit greatly differing amounts of air per cycle at different speeds of crankshaft rotation, it was necessary to superimpose manual controls to compensate for this; otherwise, a reduction of crankshaft speed would result in the admission of an excessive amount of blast air with consequent "killing" of the engine. On the other hand, an increase of crankshaft speed would result in a deficiency of blast air and consequent defective combustion.

For the past 25 or 30 years compression igni-

2

tion engines, frequently referred to as "diesel" engines, have been fueled by one or more systems of so-called "solid injection." In such systems, liquid fuel has been injected at a high pressure of the order of 10,000 p. s. i. through jets or nozzles by hydraulic pressure alone and without any air blast. These engines have all operated substantially on the constant volume combustion cycle and have consequently been characterized by maximum firing pressures of the order of twice the compression pressure. As a result of this pressure rise of about 100% above compression pressure, all modern diesel engines have suffered from a high ratio of maximum firing pressure to mean effective pressure, and have necessarily been of extremely heavy construction. So-called "diesel" engines have therefore developed into prime movers which, by comparison with gasoline engines, are costly, bulky, and heavy.

In order to reduce the cost, bulk, and weight of compression ignition engines, it is necessary to reduce the ratio of maximum firing pressure to mean effective pressure. One way of achieving this reduction is to return to the constant pressure combustion cycle of the true diesel engine. No method of achieving constant pressure combustion in a compression ignition engine has ever been discovered except by blast injection of the fuel. Notwithstanding the desirable attributes of the constant pressure combustion cycle engine, it has failed to compete successfully with the constant volume cycle engine for no reasons other than the operating hazards, the unreliability, the expense, and the inefficiency of the blast injection systems available up to this time.

The present invention has for its principal object the provision of fuel injection apparatus incorporating a new and improved blast injection system. Other objects are to provide such apparatus (a) which permits the compression ignition engine to enjoy the advantages of the constant pressure mode of combustion without paying the intolerable penalties exacted by prior blast injection systems, (b) which is particularly adapted for use with crude fuels, such as low quality liquid fuels, and suspensions of finely pulverized solid fuels, such as coal, in liquid vehicles, (c) which achieves rapid injection and fine division of fuel particles without recourse to excessively high fluid pressures, (d) which achieves a constant pressure combustion cycle and thereby avoids the high cylinder pressures and combustion shock which create such structural and mechanical problems in the contem-

porary high output compression ignition engines operating on the constant volume cycle of combustion, (e) which avoids the mechanical complication and numerous manual controls previously required to actuate the fuel and air controls of engines employing blast injection systems (f) wherein the blast pressure is automatically proportioned to the varying compression pressure of the engine cylinder, particularly in the case of supercharged engines (g) wherein the amount, by volume, of blast vapor per cycle is proportional to the amount, by volume, of fuel per cycle, the proportional volumes of air and fuel being independent of the cyclical frequency of injection, (h) which makes possible the entirely automatic adjustment of the quantity and pressure of blast air to the requirements of the engine over the complete spectrum of operating conditions without recourse to mechanically actuated valves in the injector unit, (i) wherein the blast air of each cycle of operation is derived directly from the working cylinder of the compression ignition engine on each compression stroke (j) wherein the usual blast air compressor and storage receiver are eliminated, and (k) wherein high pressure air piping, external to the engine, is eliminated.

In the drawings, Figs. 1 and 2 are schematic diagrams showing the injection system of the invention with its moving components in two combinations of positions assumed at two stages in the cycle of operations. In Fig. 1 the fuel pump is about to begin its delivery stroke and the piston in the engine cylinder is about to begin its compression stroke. In Fig. 2 the fuel pump has just completed delivery and the engine piston is at top dead center of its compression stroke. Fig. 3 is an elevational section taken on line 3—3 of Fig. 6 of an injector embodying the invention. Figs. 4 and 5 are other elevational sections taken on lines 4—4 and 5—5 respectively of Fig. 6. Fig. 6 is a plan view. Figs. 7 through 19 are cross sectional views of the injector taken along the lines 6—19 shown in Figs. 3, 4, and 5.

In Figs. 1 and 2 of the drawings, the apparatus of the invention is illustrated diagrammatically. An analysis of these diagrammatic drawings will be helpful in an understanding of the later drawings (Figs. 3—19) of an embodiment of the invention as applied in practice to a fuel injector. Only one cylinder of a two-stroke cycle engine is shown, but it is to be understood that the invented system is equally applicable to a multi-cylinder engine or to a four-stroke cycle engine.

Referring now to Fig. 1, engine piston 30 is arranged for reciprocation in cylinder 31 in the manner customary in internal combustion engines of the compression ignition type. An injector nozzle 32 provided with spray orifices 33 extends into the combustion chamber. A fuel pump, generally indicated as 34, which includes a plunger 35 reciprocated by a cam (not shown), delivers fuel to the nozzle along a course in a manner hereinafter described in detail. Tank 36 supplies fuel to the pump through passage 37.

Housing 38 contains a cylindrical chamber 39 which serves as an accumulator for compressed air, as later described. Formed in the housing in coaxial relation to chamber 39 are two guide bores 41 and 42 within which is arranged a hollow multiple piston 43. Within air accumulator chamber 39 and biased against piston 43 is a pre-loaded spring 44. A third guide bore 45 extends downward through the center of the housing co-

axially with bores 41 and 42, and within the bore is disposed plunger 46 which cooperates with piston 43, as later described. Preferably plunger 46 is a separate element, and it is so illustrated, but it may be made integral with piston 43. It is to be observed that stem 47 of plunger 46 is of smaller diameter than that of the main body of the plunger so that an annular clearance 48 is provided in the lower part of bore 45. Two more bores 49 and 51 are formed in the unit coaxial with bore 45 and within them are respectively arranged a tappet 52 and a fuel admission valve 53.

Continuing with the diagrammatic drawing shown in Fig. 1, fuel delivered by pump 34 advances through tubing 54 into passage 55 which extends downward through the housing. Passage 55 turns horizontally as passage 56 to cross between bores 49 and 51 to communicate with passage 57. Passages 56 and 57 are illustrated as lying in horizontal alignment, but in actual practice they will approach each other at an acute angle. A branch passage 58 leads upward from passage 56 and at its upper end is formed to receive a check valve 59, preferably of the ball type. Branch 58 communicates with passage 60 beyond valve 59. Passage 60 extends horizontally between bores 45 and 49 to communicate with passage 61. Passages 60 and 61 are illustrated as lying in alignment but in actual practice they will approach each other at an acute angle. Passage 61 terminates at vertical bore 62 within which is disposed a shuttle valve, generally indicated as 63, adapted to reciprocate in the bore in response to fuel and compressed air pressures in the manner later described.

Shuttle valve 63, which has three cylindrical lands 64, 65, and 66 with intermediate reduced portions 67 and 68, is free to move axially in a fluid-sealing fit in bore 62. This valve has a boss 69 at its upper end for abutment with housing wall 70 when the valve moves to its upper limit of travel, and wall 71 has a boss 72 extending upward therefrom which acts as a stop 45 for the valve when it moves to its lower limit of travel. A communicating duct 73 extends axially of the valve from boss 69 to a point where it registers with passage 74 when the valve is at its upper limit of travel. The upper end of duct 50 73 has a plurality of radial ports 75 and its lower end has a plurality of ports 76. The lands of the valve control the passages leading into bore 62 in the manner later to be described. Beyond bore 62 passage 74 serves as a continuation of 55 the fuel transfer means and leads downward, as passage 77, and then horizontally, as passage 78, to bore 51. Fuel passing through the foregoing system of passages, that is through 54, 55, 56, 58, 60, 61, 74, 77, and 78, under conditions 60 later described, impinges upon the differential surface area 79 of valve 63 to lift the latter thus permitting fuel to pass through duct 80 and orifices 33 to the combustion chamber.

Further continuing with the diagrammatic drawing shown in Fig. 1, within housing 38 there is also arranged a compressed air accumulator system comprising air accumulator chamber 39 and a series of passages extending from accumulator 39 to nozzle orifices 33. Passage 81 extends horizontally from the injector nozzle 32 and then turns vertically upward as passage 82. At the upper end of passage 82 is disposed a check valve 83, preferably of the ball type as illustrated. Two horizontal branches 84 and 70 85 lead from the vertical passage 82 to communi-

cate with bore 62. Continuing beyond bore 62 are two more air passages 86 and 87, the first of which extends upward as passage 88 and turns inward as passage 89 to bore 42, and the other of which extends upward as passage 90, then inward as passage 91, and then downward as passage 92 into chamber 39. The end portion of downward passage 92 is located in a sleeve 93 which projects downward from the top wall 94 of hollow piston 43. The lower end of sleeve 93 is spaced from the bottom wall 95 of piston 43. The top wall 94 is provided with a plurality of apertures 96 which permit air communication between chamber 97 of the piston and accumulator chamber 39. A lateral duct 98 extends horizontally from the lower portion of passage 90 to the top end portion of bore 62 above shuttle valve 63. Passage 99 vents the space 100 below the minor diameter of piston 43.

Before describing the cycle of operation of the apparatus during fuel injection, the general observation is made that the moving parts are normally thrust in one direction or the other by differential pressures produced on the one hand by compressed air from the engine piston and on the other hand by fuel from the fuel pump. The further general observation is made that the pressure of such fuel delivered by the fuel pump generates axial forces to act upon the movable elements which are in excess of the maximum opposing forces generated by such air pressure.

Referring again to Fig. 1, the engine piston 30 is at bottom dead center about to begin its compression stroke; and fuel pump 34 is about to begin its delivery stroke. The conditions prevailing within the apparatus at this stage are as follows: Air accumulator piston 43, plunger 46, tappet 52, fuel admission valve 53, shuttle valve 63, check valve 59, and check valve 83 are all in down position. An accumulation of air under pressure remaining at the completion of the preceding cycle is trapped in the system comprising air accumulator chamber 39, piston chamber 97, passages 92, 91, 90, 87, and 98 and the upper portion of bore 62. An accumulation of fuel under pressure, remaining at the completion of the preceding cycle, is trapped between check valve 59 and fuel admission valve 53 in the system between them comprising passage 60, bore 45, passage 61, bore 62 (between lands 65 and 66) and passages 74, 77, and 78. Air in engine cylinder 31 is at low pressure and the same low pressure pertains in the system comprising orifices 33, duct 80, passages 81 and 82, branch 85, the bore 62 (between lands 64 and 65) passages 86, 88, 89, and space 101 in bore 41. Fuel in tubing 54, passages 55, 56, and 57 is also at low pressure since the fuel plunger 35 has not yet cut off the spill port on its upward stroke.

As plunger 35 cuts off its spill port and begins to deliver fuel, pressure builds up in the fuel tubing 54, passages 55, 56, and 57, and as soon as it exceeds the air pressure exerted downwardly on shuttle valve 63, it begins to displace the latter valve upwardly. As valve 63 moves upwardly, its reduced portion 67 establishes communication between passages 86 and 87 thereby to equalize the air pressures in chamber 39 and space 101 in bore 41. This is of importance since the transfer of the air pressure prevailing in accumulator chamber 39 to space 101 of bore 41 causes a substantial increase in the upward force exerted on the accumulator plunger and a consequent diminution of the net downward force. Such diminution of force brings within

practical limits the requirements of fuel pressure necessary to lift plunger 46 from the bottom limit of its travel for the purpose of fuel charging, as later appears. Just before reduced portion 67 opens communication between passages 86 and 87, land 65 cuts off branch 85 so that air at accumulator pressure is prevented from escaping through branch 85, passages 82, 81, and duct 80 into cylinder 31. As the valve 63 moves upward, duct 84 is brought into the balanced air accumulator system so that accumulator chamber pressure is exerted upon air check valve 83 to hold it closed. Fuel check valve 59 remains closed at this stage because of the excess of trapped fuel pressure over pump pressure. Fuel admission valve 53 also remains closed at this stage since the net force exerted upon it is downward.

Refer now to Fig. 2, when shuttle valve 63 reaches the upper limit of its travel, fuel pressure in tubing 54, passages 55, 56, 57, and 58 is built up by pump 34 to a pressure in excess of that of the fuel trapped under plunger 46 so that check valve 59 opens. Fuel then enters passage 60, bore 45, and clearance 48 to displace plunger 46 upwardly against the combined bias of spring 44 and the differential downward force of air pressure on piston 43. Piston 43 is displaced upwardly and as it moves into chamber 39 it transfers air from the upper side of the piston through apertures 96, chamber 97, passages 92, 91, 90, 87, bore 62, and passages 86, 88, and 89 into the space 101 in bore 42; and since the volume of the trapped air is reduced by the rising piston, its pressure is increased. Tappet 52 moves to the upper limit of its travel because the fuel pressure in passages 56 and 57 is greater than the fuel pressure in passages 60 and 61 by the amount required to open check valve 59. Check valve 83 is still seated since the pressure of air in cylinder 31 transmitted through duct 80 and passages 81 and 82 has not as yet achieved a value as high as that of the trapped air in the balanced accumulator system.

It should be here observed that when valve 63 is in its top position of travel, ports 75, duct 73, and ports 76 of shuttle valve 63 establish communication between the air accumulator system and the differential surface area 79 of valve 53 through passages 74, 77, and 78. Accordingly, the residual fuel pressure on such area drops to the pressure in the air accumulator system. The prime function of duct 73 and its associated ports is to provide some lubrication by fuel of the top land 64 of the shuttle valve 63, but it also serves to make the fuel pressure on the differential surface area 79 of the valve 53 determinate and relatively low at this point in the cycle of events.

As the engine piston continues upward from the position shown in Fig. 1, the pressure of the air in the cylinder 31 and in passages 81 and 82 continues to increase. When such pressure exceeds the pressure of the air in the balanced air accumulator system, check valve 83 is forced open and air from cylinder 31 passes around reduced portion 67 of shuttle valve 63 and follows in a divided course, one portion advancing along passages 86, 88, and 89 into space 101 in bore 42 and the other portion advancing along passages 87, 90, 91, and 92 through chamber 97 and apertures 96 into chamber 39. As the air pressure continues to increase in cylinder 31, the same increasing pressure pertains throughout the air accumulator system. In the meantime fuel pump plunger 35 continues its pumping stroke and the fuel pressure increases to its maximum

pressure to force plunger 46 and piston 43 upward. The fuel storage system comprising tubing 54, passages 55, 56, 57, 58, 60, and 61, and bore 45 is filled with fuel at maximum pressure.

The fuel pump plunger now uncovers the spill port and there is an immediate drop in fuel pressure in tubing 54, passages 55, 56, 57, and 58 and the lower portion of bore 62. Check valve 59 closes but the position of land 66 of shuttle valve 63 is such that the fuel thus cut off remains trapped for an instant in bore 45 and passages 60 and 61. Because of the fuel pressure drop in passage 57 and the lower portion of bore 62, shuttle valve 63 moves rapidly downward toward its lower limit of travel in response to the air pressure exerted upon its upper end. As valve 63 reaches its lower limit of travel, reduced portion 68 opens communication between passages 61 and 74 and reduced portion 67 opens communication between passages 86 and 85.

When passages 86 and 85 are connected, air accumulated at maximum pressure in space 101 is forced through passages 88 and 96 around reduced portion 67 into branch 85, passages 82 and 81, and into the annular recess 102 whence it flows radially inwardly into duct 89 through the annular clearance 103 between lip 104 and housing portion 105. Simultaneously passages 61 and 74 have been brought into communication so that fuel in the storage system of passages 60, bore 45, and passage 61 (valve 59 now being closed) is forced through passages 74, 77, and 78, as will soon be described. The pressure of such fuel acts upon differential surface 79 to lift valve 53. The drop in fuel pressure in bore 45 allows piston 43 to descend in response to the combined forces produced by the air pressure in accumulator chamber 39 and the spring 44. Plunger 46 is displaced downwardly by piston 43 and forces the accumulated fuel around valve 53. It should here be recalled that fuel pressure in passages 56 and 57 dropped when the fuel pump spilled and consequently the fuel pressure on the differential area 79 is opposed to such lesser extent. When valve 53 is lifted, fuel emerges from outlet 106 in the form of a cylindrical sheath coaxial with duct 89. Compressed air blasted through duct 86, as previously described, intercepts the fuel sheath and it is apparent that a desirable mixture takes place between the pulverized fuel and the blast of air. The mixing occurs in the top zone 108 of duct 89. Orifices 33, have, therefore, a merely directional function in guiding the mixture into the combustion chamber in radial rays of finely dispersed droplets.

In connection with the function of duct 73 in shuttle valve 63, it is pointed out that the air displaced from chamber 39, as previously described, passes downwardly through apertures 96 into chamber 97 and thence upwardly through passage 92 in sleeve 93. Consequently any free fuel which may have been carried to the bottom of the chamber 97 in the accumulator piston 43 by way of duct 93 will be carried out through passage 92 in sleeve 93 and transferred by the moving air through passages 92, 91, and 90 around reduced portion 67 and through passages 86, 88, and 89 into space 101 in bore 41 under the differential area of the piston.

The spring in fuel check valve 59 is provided to ensure that the ball 40 seats without delay upon the cessation of fuel flow from the injection pump to the fuel accumulator. Check valve 59 is of the type which can be opened only when there is an actual flow of fuel past it in one di-

rection. If there is no flow of fuel, the valve remains closed.

The large spring 44 is provided in the air accumulator chamber 39 for the following reason: The design of the differential air piston 43 is such that the air pressure acting on its differential area during injection bears a fixed relationship to the air pressure on its upper side. It is desirable that the pressure on the differential area should be proportionably somewhat higher when the absolute pressure on the upper side of the piston is low. By the provision of the spring, a downward force on the piston is furnished independent of air pressure and the desired end is achieved.

A further reason for providing that the air feeding the differential area under the accumulator piston 43 should come from the upper side of this piston is that when the operation of the engine is changed so that the compression pressure in the engine cylinder falls, means must be provided for dropping the air pressure on the upper side of the differential air piston to the new required value. Were it not for the action of the shuttle valve 63, the air check valve 83 would prevent reduction of air pressure on the upper side of the accumulator piston to a value consistent with reduced compression pressure in the engine cylinder.

Referring now to Figs. 3 through 19, the invention is shown embodied in a fuel injector. The same reference numerals, with the addition of "a," are applied to the parts in the injector corresponding to the parts shown in the diagrammatic drawings. It is believed, in light of the preceding detailed explanation of the diagrammatic drawings, that no detailed explanation of Figs. 3 through 19 need be given.

While there has been hereinbefore described an approved embodiment of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

What I claim is:

1. A fuel injector of the type described comprising a housing; an orificed nozzle; a fuel accumulator; an inlet passage to supply fuel pumped from an outside source to the accumulator; a first check valve in said passage; a delivery passage from the fuel accumulator to the nozzle; an injection valve controlling said delivery passage; an air accumulator; a piston having a head with opposed pressure responsive surfaces disposed in the air accumulator and a piston stem having a pressure responsive surface disposed in the fuel accumulator; an air passage leading from the nozzle to the air accumulator and having two branches opening into the accumulator on opposite sides of the piston head; a check valve in one of the branches; and a shuttle valve in communication with the fuel inlet and air passages and movable to its opposite limits of travel by fuel pressure and air pressure respectively, said valve controlling the fuel delivery passage and both branches of the air passage.

2. A fuel injector of the type described comprising a housing; an orificed nozzle; an injection valve openable inwardly in response to fuel pressure; a fuel accumulator; an inlet pas-

usage to supply fuel pumped from an outside source to the accumulator; a first check valve in the inlet passage; a fuel delivery passage connecting the fuel accumulator and the injection valve; an air accumulator; a differential piston having a head with opposed pressure responsive surfaces of different areas disposed in the air accumulator and a stem extending into the fuel accumulator, said piston being adapted to move through the air accumulator in response to fuel pressure on the stem thereby to displace air from one portion of the accumulator and to provide a chamber of increasing size for the reception of air displaced from said one portion of the accumulator; a passage from the nozzle having two branches opening into the air accumulator on opposite sides of the piston head; a second check valve in the last mentioned passage; a shuttle valve having opposed surfaces thereon to reciprocate the valve in response to fuel and air pressure respectively; means connecting the fuel inlet passage and one of the shuttle valve opposed surfaces; means connecting the air accumulator and the opposite shuttle valve surface; means on the shuttle valve to control the flow of fuel from the fuel accumulator to the injection valve; means on the shuttle valve to control the flow of air from the air accumulator to the nozzle; and means on the shuttle valve to permit the flow of air from the nozzle to the air accumulator.

3. A fuel injector of the type described comprising a housing; an orificed nozzle; an injection valve openable inwardly in response to fuel pressure in the delivery passage; a fuel accumulator; an inlet passage to supply fuel pumped from an outside source to the accumulator; a first check valve in the inlet passage; a fuel delivery passage from the fuel accumulator to the injection valve; an air accumulator; a piston having a head with opposed pressure responsive surfaces disposed in the air accumulator; a plunger associated therewith and having a pressure responsive surface disposed in the fuel accumulator; a preloaded spring engaging one of the pressure responsive surfaces of the piston head; an air passage from the nozzle having two branches opening into the air accumulator on opposite sides of the piston head; a second check valve in the air passage; a limited bore in the housing; a shuttle valve slideable in said bore and comprising a cylindrical member having opposite end pressure responsive surfaces adapted to reciprocate the valve in response to fuel and air pressures respectively; means connecting the fuel inlet passage and one of said end surfaces; means connecting the air passage and the other of said end surface; means on the valve to control the flow of fuel from the fuel accumulator to the injection valve; and means on the valve to control the flow of air between the air accumulator and the nozzle; said shuttle valve moving to one limit of travel in response to fuel pressure during delivery of fuel through the inlet passage and cutting off communication between the injection valve and the nozzle and the fuel and air accumulators respectively thus trapping fuel and air in their respective accumulators, said shuttle valve then moving to the other limit of travel in response to air pressure in the air accumulator when fuel pressure on the shuttle valve drops at the completion of fuel delivery to the fuel accumulator thus opening communication between the injection valve and the fuel accumulator and between the nozzle and air accumulator, said piston mov-

ing in one direction through the air accumulator in response to fuel pressure on the stem thus to displace air from the portion of the air accumulator which is decreasing in volume to the portion of the air accumulator which is increasing in volume and moving in the other direction through the air accumulator in response to the pressure of the compressed air to force air from the portion of the air accumulator of now decreasing volume and fuel from the fuel accumulator through their respective delivery passages to the nozzle and injection valve respectively.

4. A fuel injector of the type described comprising a housing; an orificed nozzle adapted to disperse an emulsion of air and fluid fuel; an air accumulator; an air supply passage from the nozzle to the air accumulator; a check valve in the air supply passage; a piston reciprocable in the air accumulator, said piston having two axially opposed pressure responsive surfaces of unequal area; a fuel accumulator, a fuel inlet passage to conduct fuel under pressure from an outside source to the fuel accumulators; a check valve in the fuel inlet passage; a plunger reciprocable in the fuel accumulator, said plunger being adapted to move in unison with the air accumulator piston; a differential fuel valve; means whereby said fuel accumulator piston, when at its discharge limit of travel, retains said differential fuel valve in closed position; a passage from the fuel accumulator to the differential area of the differential fuel valve; a first branch of the fuel inlet passage to communicate fuel supply pressure to the major area of the differential fuel valve; a landed shuttle valve in communication with the fuel inlet passage and with the air supply passage, said shuttle valve having two axially opposed surfaces to provide reciprocation of the shuttle valve in response to alternating excesses of fuel pressure and air pressure on said axially opposed surfaces respectively; means on the shuttle valve to control the flow of fuel through the passage from the fuel accumulator to the differential area of the differential fuel valve; a fuel valve; means on the shuttle valve to control the flow of air through the air supply passage to the major area of the air accumulator piston; means on the shuttle valve to control the flow of air from the minor area of the air accumulator piston to the air supply passage between the nozzle and the air accumulator; and means on the shuttle valve to balance the pressure of air between the major and minor areas of the air accumulator piston.

5. A fuel injector of the type described comprising a housing; an orificed nozzle adapted to disperse an emulsion of air and fluid fuel; an air accumulator; an air supply passage from the nozzle to the air accumulator; a check valve in the air supply passage; a piston in the air accumulator, said piston having two axially opposed pressure responsive surfaces of unequal area; a fuel accumulator; a fuel inlet passage to conduct fuel under pressure from an outside source to the fuel accumulator; a check valve in the fuel inlet passage; a plunger in the fuel accumulator, said plunger being adapted to move in unison with the air accumulator piston; a differential fuel valve; a tappet to retain the differential fuel valve in closed position when the fuel accumulator piston is at its discharged limit of travel; a passage from the fuel accumulator to the differential area of the differential fuel valve; a landed shuttle valve having two axially opposed surfaces to provide reciprocation of the

shuttle valve in response to alternating excesses of fuel pressure and air pressure on said axially opposed surfaces respectively; a first branch of the fuel inlet passage to communicate fuel supply pressure to the major area of the differential fuel valve; a second branch of the fuel inlet passage to communicate fuel supply pressure to the first of the axially opposed surfaces of the shuttle valve; means on the shuttle valve to control the flow of fuel through the passage from the fuel accumulator to the differential area of the differential fuel valve; means on the shuttle valve to control the flow of air from the air supply passage to the major area of the air accumulator piston; means on the shuttle valve to control the flow of air from the minor area of the air accumulator piston to the air supply passage between the nozzle and the air accumulator; means on the shuttle valve to control the flow of air between the major and minor areas of the air accumulator piston; a passage communicating air pressure from the major area of the air accumulator piston to the second of the axially opposed surfaces of the shuttle valve; and means whereby any accretion of fuel in the air accumulator is expelled through said nozzle.

6. A fuel injector, according to claim 5, having a passage from the plunger bore to deliver any excessive charge of fuel out of the injector.

7. A fuel injector of the type described comprising a housing; an orificed nozzle adapted to disperse an emulsion of air and fluid fuel; an air accumulator; an air supply passage from the nozzle to the air accumulator; a check valve in the air supply passage; a piston reciprocable in the air accumulator, said piston having two axially opposed pressure responsive surfaces of unequal area; a fuel accumulator, a fuel inlet passage to conduct fuel under pressure from an outside source to the fuel accumulator; a check valve in the fuel inlet passage; a plunger reciprocable in the fuel accumulator, said plunger being adapted to move in unison with the air accumulator piston; a differential fuel valve; means whereby said fuel accumulator piston, when at its discharge limit of travel, retains said differential fuel valve in closed position; a passage from the fuel accumulator to the differential area of the differential fuel valve; a first branch of the fuel inlet passage to communicate fuel supply pressure to the major area of the differential fuel valve; a landed shuttle valve in communication with the fuel inlet passage and with the air supply passage, said shuttle valve having two axially opposed surfaces to provide reciprocation of the shuttle valve in response to alternating excesses of fuel pressure and air pressure on said axially opposed surfaces respectively; means on the shuttle valve to control the flow of fuel through the passage from the fuel accumulator to the differential area of the differential fuel valve; means on the shuttle valve to control the flow of air through the air supply passage to the major area of the air accumulator piston; means

on the shuttle valve to control the flow of air from the minor area of the air accumulator piston to the air supply passage between the nozzle and the air accumulator; and means on the shuttle valve to balance the pressure of air upon the major and minor areas of the air accumulator piston.

8. A fuel injector of the type described comprising a housing; an orificed nozzle adapted to disperse an emulsion of air and fluid fuel; an air accumulator; a check valve in the air supply passage; a piston reciprocable in the air accumulator, said piston having two axially opposed pressure responsive surfaces of unequal area; an air supply passage from the nozzle to the air accumulator including two branches, one of which leads to the larger of the opposed pressure responsive surfaces and the other of which leads to the smaller of the opposed pressure responsive surfaces; a fuel accumulator; a fuel inlet passage to conduct fuel under pressure from an outside source to the fuel accumulator; a check valve in the fuel inlet passage; a plunger reciprocable in the fuel accumulator, said plunger being adapted to move in unison with the air accumulator piston; a differential fuel valve; means whereby said fuel accumulator piston, when at its discharge limit of travel, retains said differential fuel valve in closed position; a passage from the fuel accumulator to the differential area of the differential fuel valve; a first branch of the fuel inlet passage to communicate fuel supply pressure to the major area of the differential fuel valve; a landed shuttle valve having two axially opposed surfaces to provide reciprocation of the shuttle valve in response to alternating excesses of fuel pressure and air pressure on said axially opposed surfaces respectively; a second branch of the fuel inlet passage to communicate fuel supply pressure to the first of the axially opposed surfaces of the shuttle valve; a passage communicating air pressure from the major area of the air accumulator piston to the second of the axially opposed surfaces of the shuttle valve; means on the shuttle valve to control flow of fuel through the passage from the fuel accumulator to the differential area of the differential fuel valve; means on the shuttle valve to control the flow of air through the air supply passage to the major area of the air accumulator piston; means on the shuttle valve to control the flow of air from the minor area of the air accumulator piston to the air supply passage between the nozzle and the air accumulator; and means on the shuttle valve to balance the pressure of air between the major and minor areas of the air accumulator piston.
